**CARRIER FOR CAROUSEL SLIDE MAGAZINE OR THE
LIKE**

The invention described herein may be manufactured and used by or for the Government without the payment to me of any royalty thereon.

BACKGROUND OF THE INVENTION

1. Field of the Invention

This invention is an improved carrying or storage device for carousel slide magazines or other articles containing a central aperture. The carrying device is capable of adjustment for carrying different numbers of articles through the use of vertically adjustable members extending through the central apertures of the carried articles.

2. Description of the Prior Art

Prior carrying devices for carousel slide magazines have been bulky and expensive rectangular box-shaped carriers which were not capable of providing adjustable carrying capacity.

SUMMARY OF THE INVENTION

The present invention provides a light, compact, adjustable, and inexpensive carrying device for articles containing a central aperture, especially carousel slide magazines. At least one self-locking telescoping connecting member is provided connecting two parallel planar elements between which are stacked the carried articles. The entire assembly is held in place by a fastening device which engages the connecting member. Each planar element may be provided with a hinge so that it can be folded over on a similar element so that the invention may be changed from dual- to single-stack-carrying configuration.

Accordingly, it is an object of this invention to provide a lightweight, inexpensive adjustable capacity carrying device for carousel slide magazines and other articles containing a central aperture.

It is a further object of this invention to provide a carrying device for carousel slide magazines and other articles containing a central aperture having at least one adjustable telescoping member connecting two parallel planar hinged elements so that maximum versatility and adjustment are achieved.

BRIEF DESCRIPTION OF THE DRAWINGS

FIG. 1 is an elevational view partially in section of one embodiment of the invention;

FIG. 2 is an elevational view of the invention in the folded configuration;

FIG. 3 is a view in elevation partly in section of one embodiment of the telescoping connecting member;

FIGS. 4 and 5 are elevational views partly in section of alternative embodiments of the telescoping connecting member;

FIGS. 6a and 6b are elevational views, partially in section, of an alternative embodiment of the telescoping connecting member;

FIG. 7 is a plan view of an alternative embodiment of the invention; and

FIGS. 8a and 8b are plan views of the top and base elements of the invention.

DESCRIPTION OF THE PREFERRED EMBODIMENT

Referring to FIG. 1 the half of the carrying device shown in section comprises a planar base 1, a planar top element 2 containing a central aperture 2a, a telescoping member 3 connecting elements 1 and 2, and a fastening device 4 which fastens to the connecting member 3 in a manner such that a force is exerted on planar top element 2 to secure top element 2, the carried articles 12, and base element 1 in stacked relationship. The cap 4 may include any desired number of internally threaded, successively reduced portions adapted to threadedly engage the threads of selected parts of the connecting assembly 3 depending on the number of articles to be carried. The described structure is duplicated in the other half

of the carrying device to form a carrying device capable of carrying two stacks of carried elements.

Referring to FIG. 8a it can be seen from the top view of the top planar element 2 that the top planar element 2 comprises two generally circular planar elements 5, 6 placed in horizontal alignment. The edges 7, 8 of the planar elements 5, 6 are straight so that the planar elements may be joined by hinges 9. Circular central apertures 120, 121 are provided in elements 5, 6 and a lip 10 as in FIG. 1 is provided on top planar element 2 around the periphery of each of joined elements 5, 6. Referring to FIG. 8b the base planar element 1 is similarly constructed of two generally circular planar elements 130, 131 having edges 132, 133 which are straight. The elements 130, 131 are joined by hinge means 134 at these straight edges 132, 133. A lip 11 is provided around the outer edge of base planar element 1. The base planar element 1 is further provided with an internally threaded cylindrical collar 28 for securing the connecting member assembly 3.

Referring to FIGS. 1 and 3 the connecting member 3 is comprised of three concentric cylindrical elements, 13, 14 and 15. The element 13 is provided with thread 16 around the lower end of the outer surface so that the connecting member assembly 3 can be removably secured to the base member 1 through engagements with the threaded collar 28. A threaded portion 17 is also provided at the upper end of element 13 to permit attachment of the fastening means 4. A projecting lug 18 directed radially inward from the surface of element 13 is provided at the upper end of element 13 so that the lug may be slidably engaged in a groove 19 to be provided in element 14. Element 14 is of a hollow cylindrical configuration and is made to fit within element 13 so that they are in concentric axial alignment. A groove 19 is provided in the sidewall of element 14 so that lug 18 of element 13 may be slidably engaged. Thus, the movement of element 14 along its common longitudinal axis with element 15 is guided by the engagement of lug 18 and groove 19. An extension 20 of groove 19 is provided in a direction perpendicular to groove 19 at the lower end of element 14 so that the elements 13 and 14 may be locked in place at the limit of the extension of element 14 by a clockwise torque applied to the upper end of element 14. A thread 21 is provided on the exterior surface at the upper end of element 14 to permit attachment of the fastening means 4. A projecting lug 22 is provided at the upper end of element 14 so that the lug may be slidably engaged in a groove 23 to be provided in element 15. Element 15 is a hollow cylindrical element constructed to fit within element 14 so that their longitudinal axes are aligned and they are in concentric relationship. A groove 23 is provided in the sidewall of element 15 so that lug 22 of element 14 may be slidably engaged so that the relative movement of elements 14 and 15 along their common longitudinal axis is guided by lug 22 and groove 23. An extension 24 of groove 23 is provided in a direction perpendicular to groove 23 at the lower end of element 15 so that elements 14 and 15 may be locked in place at the limit of extension of element 15 by a clockwise torque applied to the upper end of element 15. A thread 25 is provided on the exterior surface at the upper end of element 15 to permit attachment of fastening means 4. A bottom 26 is provided in element 15 so that it may be used for storage of small items.

For ease of description only one projecting lug and interengaging groove per telescoping section was illustrated and described; however, any number of lugs and grooves needed to impart stability and strength to the invention can be used.

The fastening member 4 of FIG. 1 is comprised of three stepped cylindrical portions, 30, 31 and 32 in this embodiment, although any desired number of stepped portions may be provided, on the inside of which are provided threads 33, 34, 35 adapted to threadably engage threads 17, 21, 25, respectively, on elements 13, 14, 15 of connecting member assembly 3. Cylindrical portion 32 is provided with an exterior thread 36 which is adapted to threadably engage threads 34 of the fastening means 4 of the other half of the invention so that the two fastening means may be threadably secured to one

another as shown in FIG. 2. A groove 38 is provided around the periphery of cylindrical section 31 and receives loop 39 of carrying handle 40.

Maximum versatility and adaptability is provided by hinges 9 and 134 connecting the two halves of top planar member 2 and the two halves of base planar member 1 so that the two halves may be superimposed when it is desired to utilize the invention to carry a single stack as shown in FIG. 2. Interlocking feet 41, 42 are provided on base planar member 1 so that the two halves of base planar member 1 are securely held together when in the folded configuration. The cylindrical collar 28 plus the lip 11 serve as a base for the invention in this configuration to prevent the surface of base planar member 1 from resting directly on the floor.

In operation, if it is desired that a full load of carousel slide magazines, six for this embodiment, be carried, the invention is placed in the configuration shown in FIG. 1. The connecting member assembly 3 is attached to the base planar member 1 by threadably engaging the outer telescoping cylindrical member 13 and internally threaded cylindrical collar 28. The inner telescoping member 15 is pulled upward until both it and member 14 have reached the extent of travel permitted by lugs 18 and 22 and grooves 19 and 23. The member 15 is then twisted in a counterclockwise direction, thus locking members 15 and 14 in their extended positions through engagement of lugs 18 and 22 and groove extensions 20 and 24. This procedure is repeated for the other half of the invention so that both connecting member assemblies are fully extended. The first two carousel slide magazines 12 are then placed on the invention so that cylindrical collars 28 are fitted within the central apertures of the slide magazines. The remaining magazines are then stacked on the first two magazines and the top planar member is placed over the top magazines so that the inner telescoping member 15 projects through the central apertures 120, 121 of each half 5, 6 of the top planar member 2. The fastening means 4 is then threadably engaged with inner telescoping member 15 by means of threads 25 and 35. It should be understood that the same procedure must be carried out to secure the other half of the invention although for simplicity of description this obvious step is not explicitly detailed herein. The dimensions of the central cylindrical collars 28 and of the top and base planar members 1 and 2 are chosen so that the standard carousel slide magazine fits closely within the invention. The central cylindrical collars 28 and lips 10 and 11 prevent movement of the magazines during travel, and the top and base planar members 1 and 2 and the sides of the magazines provide protection for the contents of the magazines in inclement weather.

If it is desired to carry four magazines, then the inner telescoping member 15 is not extended, and the fastening device 4 is threadably engaged with member 14 by means of threads 21 and 34.

In a similar fashion two magazines may be carried by threadably engaging the fastening member 4 with the outer telescoping member 13 by means of threads 17 and 33. The inner telescoping members 14 and 15 are not extended in this configuration.

If it is desired to carry from one to three magazines in a single stack, the top and base planar elements 1 and 2 may be folded by hinge means 9 and 134 to superimpose their respective halves. In this configuration the connecting member assembly 3 from one half is removed and that half of the base planar member 1 is folded over on the other half and is engaged by means of the interlocking feet 41, 42. The top planar member is folded through hinge 9 and the invention is assembled for use as previously described. After one fastening means 4 is threadably attached to the single connecting assembly 3 the remaining fastening means 4 is threadably secured to the first fastening means 4 through engagement of threads 34 and 36. The carrying handle 40 is in place over the two fastening means 4 for ease in carrying the invention in this configuration. An alternative embodiment of this concept could be achieved through the use of hinge elements having a

removable pivot pin. The pin could be removed from the top and bottom hinge elements so that the two halves of the carrying device could be used independently. Provision of an extra pair of fastening means would be required, however, unless the carrying handle 40 were made to be removable.

5 In FIG. 4 is shown an alternative embodiment of the telescoping connecting member assembly 3. In this embodiment telescoping members 50, 51, and 52 are provided with threads 53, 54, and 55 at the outer top surfaces of each respectively, threads 56, 57 on the inner top surfaces of members 50 and 51, respectively, and threads 58, 59, 60 at the outer lower surfaces of each, respectively. The telescoping members are extended and locked in place by means of thread pairs 57, 60 and 56, 59. Thread 58 is used to attach the assembly to the cylindrical collars 28 on the base planar assembly 1 and threads 53, 54 and 55 are utilized to secure the fastening means 4 at the three stages of extension of the connecting member assembly. This embodiment can be used directly in place of the connecting member assembly shown in FIG. 3 and the same fastening means 4 can be used with it without modification.

10 Another alternative embodiment of the connecting member assembly is shown in FIG. 5. In this embodiment the telescoping members are locked into place when extended by means of peripheral grooves 70 and 71 and radial lips 72 and 73. Threads 74, 75, and 76 are provided on the outer top surfaces of telescoping members 77, 78, 79 for attachment of fastening means 4. Thread 80 on the outer bottom surface of member 30 77 is used to attach the assembly to the cylindrical collar 28 on base planar member 1. In operation the assembly is extended by pulling upward on the telescoping member until it locks in place. The assembly is collapsed by pushing down on the top-most element. This embodiment can be used directly in place 35 of the embodiments shown in FIGS. 3 and 4 and the fastening means 4 also can be used. The telescoping members may be made in a cylindrical embodiment or they can be constructed so that the bottom diameter is greater than the top diameter thus insuring that the elements cannot come apart if the groove and lip should become disengaged.

40 In FIG. 6a is shown another alternative embodiment of the connecting member shown in FIG. 3. This embodiment consists of telescoping members 100, 101, 102. Members 101 and 102 are provided with internal grooves 103, 104 which engage 45 inwardly projecting lugs 105, 106 from member 100, 101, respectively. Each groove is provided with extensions 107, 108 perpendicular to the length of the grooves at the bottom of the members 101, 102 to provide for locking when these members are extended. The grooves are also provided with an L-shaped extension 109, 110 at the top of the member so directed that when the projecting lug is in the right corner of the L-shaped projection an upward pull on the member will force the projecting lug down into the lower part of the L-shaped projection as shown in FIG. 6b. In this position the telescoping member is locked in to position and cannot move.

50 Thus it is now possible to use a fastening means 111 with only one inner thread 112. The dimensions of the members are chosen such that when the invention is in use an upward force 55 will be exerted on the telescoping member, thus holding them securely and positively in position. A thread 113 is provided on the outer lower surface of member 100 to attach the assembly to cylindrical collar 28 on base planar element 1. A thread 114 is provided on the outer top surface of inner 60 telescoping member 102 to threadably engage the fastening means 111 by means of thread 112. The outer upper section of fastening means 111 is dimensioned and provided with thread 115 so that it will engage thread 112 of a second fastening means 111 in a fashion similar to that shown in FIG. 2. A carrying handle can be provided in the same manner as shown in the same manner as shown in the previous embodiment of FIG. 1.

65 In FIG. 7 is shown a cloverleaf arrangement of my invention adapted to store four stacks of magazines. The various sections 70 can be assembled from the members previously

described. This embodiment is intended primarily for storage and may be extended to include any convenient number of sections.

The invention may be made from plastic, wood, or metal by any conventional method, although it is considered that injection molding from a plastic material will provide the most inexpensive and satisfactory product. An embodiment containing a maximum of three extendible elements has been described herein for purposes of illustration as this size has been found to be most useful and convenient; however, extension of the capacity to any desired number of extendible sections can be accomplished by application of the principles disclosed.

I claim:

1. A carrying device for carousel slide magazines or other articles containing a central aperture comprising first and second planar members in parallel spaced relationship, at least two telescoping connecting members rigidly mounted in perpendicular relationship to said first planar member and extending through central apertures provided in said second planar member, fastening means engaging said telescoping connecting members above said second planar member in a manner adapted to secure said first planar member, the carried articles, and said second planar member in stacked relationship, said first and second planar member each comprising first and second planar sections hingedly connected so that said first planar section may be folded through said hinge means to superimpose on said second planar section so the carrying device may be adapted from multiple stack capacity to single-stack capacity.

2. A carrying device for carousel slide magazines or other articles containing a central aperture comprising:

- a. first and second planar members in parallel spaced relationship;
- b. at least one telescoping connecting means, containing integral self-locking means located on separate adjacent sections of said telescoping connecting means and adapted to secure said telescoping connecting means in extended position upon adjustment and rotation relative to each other of said separate adjacent sections of said telescoping connecting means, said telescoping connecting means being rigidly mounted in perpendicular relationship to said first planar member and extending through a central aperture provided in said second planar member; and
- c. fastening means engaging said telescoping connecting means above said second planar member in a manner adapted to secure said first planar member, the carried articles, and said second planar member in stacked relationship.

3. A carrying device for carousel slide magazines or other articles containing a central aperture comprising first and second planar members in parallel spaced relationship, at least one telescoping connecting means rigidly mounted in perpendicular relationship to said first planar member and extending through a central aperture provided in said second planar member, fastening means engaging said telescoping connecting means above said second planar member in a manner adapted to secure said first planar member, the carried articles, and said second planar member in stacked relationship, said telescoping connecting means comprising a first tubular member having a first internally projecting lug near its upper rim and external screw threads on its opposite ends; a second tubular member adapted to fit concentrically within said first tubular member having external screw threads on its upper surface, and a second internally projecting lug near its upper rim and a first groove cut into its external surface, said first groove being substantially parallel to the longitudinal axis of said second tubular member and extending from its upper rim to near its lower rim, said first groove containing a perpendicular extension along the external surface of said second tubular member at the lower end of said first groove, said first groove being adapted to engage said first projecting lug; a

third tubular member adapted to fit concentrically within said second tubular member having external screw threads on its upper surface and a second groove cut into its external surface, said second groove being substantially parallel to the longitudinal axis of said third tubular member and extending from its upper rim to near its lower rim, said second groove containing a perpendicular extension along the external surface of said third tubular member at the lower end of said second groove, said second groove being adapted to engage said second projecting lug.

5 4. The device of claim 3 in which more than one telescoping connecting member is included, and said first and second planar members each comprise first and second planar sections hingedly connected so that said first planar section may be folded through said hinge means to superimpose on said second planar section so the carrying device may be adapted from multiple stack capacity to single-stack capacity.

15 5. The device of claim 4 in which each of said fastening means comprises a frustoconical cap member comprised of a series of stepped cylindrical portions having successively reduced inside and outside diameter from the bottom of said cap member to the top thereof, said cylindrical portion provided with internal threaded means for selective engagement with said tubular telescoping members.

20 6. The cap members of claim 5 wherein the uppermost smallest diameter portion is provided with external thread means for engagement with internal thread means of a portion of a cap as recited in claim 5.

30 7. The cap members of claim 6 wherein common bail means are secured to an intermediate step portion of each of said cap members whereby said cap members are interconnected.

8. The device of claim 4 in which said first and second planar sections are foldably superimposed so that the carrying device is adapted to carry one stack of carried articles, and in which the cap members of claim 7 are threadably interengaged and are attached to said telescoping connecting means whereby said common bail means forms a carrying means.

35 40 9. The device of claim 4 in which said first and second planar sections of said first planar member are provided with projections adapted to interengage when said first and second planar sections are foldably superimposed, thus securely holding said planar sections in superimposed position.

45 10. The device of claim 4 in which said first and second planar members are provided with a lip along the periphery of said first and second planar members so that excessive movement of the carried articles is prevented.

50 11. A carrying device for carousel slide magazines or other articles containing a central aperture comprising first and second planar members in parallel spaced relationship, at least one telescoping connecting means rigidly mounted in perpendicular relationship to said first planar member and extending through a central aperture provided in said second planar member, fastening means engaging said telescoping connecting means above said second planar member in a manner adapted to secure said first planar member, the carried articles, and said second planar member in stacked relationship,

55 60 65 70 said telescoping connecting means comprising a first tubular member having internal and external screw threads on the upper end thereof, a second tubular member adapted to fit concentrically within said first tubular member, said second tubular member having internal screw threads on opposite ends and internally at its upper end so that said first and second tubular members may be threadably engaged, a third tubular member adapted to fit concentrically within said second tubular member, said third tubular member having external screw threads on opposite ends thereof, so that said second and third tubular members may be threadably engaged.

75 12. A carrying device for carousel slide magazines or other articles containing a central aperture comprising first and second planar members in parallel spaced relationship, at least one telescoping connecting means rigidly mounted in perpen-

dicular relationship to said first planar member and extending through a central aperture provided in said second planar member, fastening means engaging said telescoping connecting means above said second planar member in a manner adapted to secure said first planar member, the carried articles, and said second planar member in stacked relationship, said telescoping connecting means comprising a first tubular means having external screw threads on its upper surface and a first internally projecting lip around its upper rim; a second tubular means adapted to fit concentrically within said first tubular means having external screw threads on its upper surface, a second internally projecting lip around its upper rim, and an external circumferential groove near its lower end adapted to receive said first projecting lip when said second tubular member is extended; a third tubular member adapted to fit concentrically within said second tubular member having external screw threads on its upper surface and an external circumferential groove near its lower end adapted to receive said second projecting lip when said third tubular member is extended.

13. A carrying device for carousel slide magazines or other articles containing a central aperture comprising first and second planar members in parallel spaced relationship, at least one telescoping connecting means rigidly mounted in perpendicular relationship to said first planar member and extending through a central aperture provided in said second planar member, fastening means engaging said telescoping connecting means above said second planar member in a manner adapted to secure said first planar member, the carried articles, and said second planar member in stacked relationship, said telescoping connecting means comprising a first tubular member having a first internally projecting lug near its upper rim; a second tubular member adapted to fit concentrically within said first tubular member having a second internally projecting lug near its upper rim and at least one first groove cut into its external surface, said first groove being substantially parallel to the longitudinal axis of said second tubular member and extending from near its upper rim to near its lower rim, said first groove having perpendicular extensions along the external surfaces of said second tubular member at the upper and lower ends of said first groove, the upper perpendicular extension having a further perpendicular extension substantially parallel to said first groove directed toward the lower rim of said second tubular member, said first groove being adapted to engage said first projecting lug; a third tubular member adapted to fit concentrically within said second tubular member having screw threads inscribed on its upper external surface adapted to engage said fastening means and having a second groove cut into its external surface, said second groove being substantially parallel to the longitudinal axis of said third tubular member and extending from near its upper rim to near its lower rim, said second groove having per-

pendicular extensions along the external surface of said third tubular member at the upper and lower ends of said second groove, the upper perpendicular extension having a further perpendicular extension substantially parallel to said second groove directed toward the lower rim of said third tubular member, said second groove being adapted to receive said second projecting lug.

14. A carrying device for carousel slide magazines or other articles containing a central aperture comprising:

a. first and second planar members in parallel spaced relationship, said first and second planar members each comprising first and second planar sections hingedly connected so that said first planar section may be folded through said hinge means to superimpose on said second planar section;

b. at least one telescoping connecting means, containing integral self-locking means adapted to secure said telescoping connecting means in extended position, said telescoping connecting means being rigidly mounted in perpendicular relationship to said first planar member and extending through a central aperture provided in said second planar member; and

c. fastening means engaging said telescoping connecting means above said second planar member in a manner adapted to secure said first planar member, the carried articles, and said second planar member in stacked relationship.

15. A carrying device for carousel slide magazines or other articles containing a central aperture comprising:

a. first and second planar members in parallel spaced relationship, said first and second planar members each comprising first and second planar sections hingedly connected so that said first planar section may be folded through said hinge means to superimpose on said second planar section;

b. at least one telescoping connecting means, containing integral self-locking means located on separate adjacent sections of said telescoping connecting means and adapted to secure said telescoping connecting means in extended position upon adjustment and rotation relative to each other of said separate adjacent sections of said telescoping connecting means, said telescoping connecting means being rigidly mounted in perpendicular relationship to said first planar member and extending through a central aperture provided in said second planar member; and

c. fastening means engaging said telescoping connecting means above said second planar member in a manner adapted to secure said first planar member, the carried articles, and said second planar member in stacked relationship.
